UNITED STATES PATENT OFFICE.

FRANK E. CROTTO, OF DALLAS, TEXAS, ASSIGNOR TO ROBERT T. MEADOR, TRUSTEE,
OF DALLAS, TEXAS.

WELL-WASHER.

1,384,305.

Specification of Letters Patent. Patented July 12, 1921.

Application filed January 29, 1921. Serial No. 404,849.

To all whom it may concern:

Be it known that I, FRANK E. CROTTO, citizen of the United States, residing at Dallas, in the county of Dallas and State of 5 Texas, have invented certain new and useful Improvements in Well-Washers, of which the following is a specification.

This invention has to do with well washers.

10 The object of the invention is to provide a washer having a pair of packers formed of fabric and arranged to be expanded against the casing or screen by the pressure of the cleaning fluid prior to its delivery 15 from the washer pipe. A particular feature involves the expansion of the packer sleeve against spring tension and the operation of a valve collar by the sleeve to permit the discharge of the cleaning fluid after 20 the sleeve has been expanded.

A construction designed to carry out the invention will be hereinafter described together with other features of the invention.

The invention will be more readily understood from a reading of the following specification and by reference to the accompanying drawings, in which an example of the invention is shown, and wherein:

Figure 1 is a vertical sectional view of a 30 well screen showing therein in elevation, a washer constructed in accordance with this invention and the packing sleeves not expanded,

Fig. 2 is an enlarged sectional detail 35 showing the upper end of the washer,

Fig. 3 is a detail showing one of the packing sleeves expanded and the valve collar in its open position.

In the drawings the numeral 10 designates a section of pipe which is connected in the usual way to the line of well pipe (not shown) extending down into the well. At the lower end of the pipe 10 a guide plug 11 is inserted. A pair of flanged collars 12 are fastened on the pipe in spaced relation and directed toward each other, the lower collar being immediately above the plug.

On the reduced portion of each collar the 40 end of a fabric sleeve 13 is fastened by coils of wire 14 surrounding the same and soldered together, or any other suitable fastening may be employed to secure the sleeve.

The opposite end of each sleeve is fastened 45 around the enlarged end of a sliding valve

collar 15, by means of coils of wire 14 soldered together, or is otherwise suitably fastened. Each sleeve has a diameter considerably larger than the collar portions to which they are attached and are gathered 60 and plaited at their ends. Water-tight connections must be had between the ends of the sleeves and the collars. The sleeves may be made of any suitable fabric such as duck, leather or rubber fabric or any other flexible material.

Within each sleeve a coiled spring 16 surrounds the pipe 10 between the collars and is under tension. Each sliding collar 15 has a slot 17 into which a stud 18 on the 70 pipe projects. The spring expels the collar 15 so that the stud is in engagement with the inner end of the slot. Each collar 15 has a plurality of perforations 19. The pipe 10 has perforations 20 located within 75 each sleeve and also within each valve collar 15. The springs hold the collars so that their perforations 19 are normally out of registration with the perforations 20. The pipe between the valve collars is imperfo- 80 rate.

In operation the washer is lowered into the well screen A and water or other cleaning fluid is pumped into the pipe 10. The water discharges through the perforations 85 20 within the sleeves 13, those perforations within the valve collars 15 being closed. The water entering the sleeves expands the same so that they are forced into contact with the wall of the screen as is shown in 90 Fig. 3. When one of the sleeves 13 expands it pulls its collar 15 inward against the tension of its spring 16, so that when the sleeve is fully expanded the perforations 19 will register with the perforations 20; permitting 95 the water to discharge between the sleeves and wash out the screen. The slots 17 limit the inward movement of the valve collars. When the pressure of the water is relieved the springs 16 will expand and slide 100 the valve collars outward, thus retracting the sleeves and closing the perforations 20 with the collars.

The invention is presented as including all such modifications and alterations as 105 come within the scope of the appended claims.

What I claim, is:

1. In a well washer, a pipe, a flexible sleeve surrounding the pipe and having one 110

- end fastened thereto, and a valve slidable on the pipe and connected with the sleeve, the pipe being perforated within the sleeve and also within the valve, said valve uncovering 5 the perforation when slid.
2. In a well washer, a pipe, a flexible sleeve surrounding the pipe and having one end fastened thereto, a valve slidable on the pipe and connected with the sleeve, the 10 pipe being perforated within the sleeve and also within the valve, said valve uncovering the perforation when slid, and a coiled spring within the sleeve normally holding the sleeve contracted and the valve 15 covering the perforation.
3. In a well washer, a pipe, a flexible sleeve surrounding the pipe and having one end fastened thereto, a valve slidable on the pipe and connected with the sleeve, the pipe 20 being perforated within the sleeve and also within the valve, said valve uncovering the perforation when slid, a coiled spring within the sleeve normally holding the sleeve contracted and the valve covering the perforation, and means for limiting the sliding 25 movement of the valve.
4. In a well washer, a pipe, a pair of spaced rigid collars on the pipe, flexible sleeves surrounding the pipe and each having one end gathered around one of the 30 rigid collars and fastened thereto, perforated sliding collars mounted on the pipe, the pipe being imperforate between the sliding collars and perforated within the sleeves and also within the sliding collars, 35 and coiled springs within the sleeves surrounding the pipe between the rigid and sliding collars thereof and normally under tension.
5. In a well washer, a pipe, a pair of 40 spaced rigid collars on the pipe, flexible sleeves surrounding the pipe and each having one end gathered around one of the rigid collars and fastened thereto, perforated sliding collars mounted on the pipe, 45 the pipe being imperforate between the sliding collars and perforated within the sleeves and also within the sliding collars, coiled springs within the sleeves surrounding the pipe between the rigid and sliding 50 collars thereof and normally under tension, and means for limiting the sliding movement of the sliding collars.

In testimony whereof I affix my signature.

FRANK E. CROTTO.
